UNITED STATES PATENT OFFICE.

CHARLES A. STICKNEY, OF CHICAGO, ILLINOIS.

ENGINE-CYLINDER OILER.

1,200,149.

Specification of Letters Patent.

Patented Oct. 3, 1916.

Application filed November 12, 1915. Serial No. 61,175.

To all whom it may concern:

Be it known that I, CHARLES A. STICKNEY, a citizen of the United States, residing at Chicago, county of Cook, and State of Illinois, have invented certain new and useful Improvements in Engine-Cylinder Oilers, of which the following is a specification.

This invention relates to oilers for supplying a lubricant to the cylinders in internal combustion engines, or to parts having similar oil requirements, but is especially adapted for internal combustion engine work, as it will always supply a sufficient amount of oil irrespective of the temperature under which the engine is running.

One object of my invention is to provide positive means for at all times supplying the cylinder or cylinders with a given amount of oil for each revolution of the engine.

Another object of my invention is to provide means for varying at will the amount of oil to be fed to each cylinder or cylinders.

Another object of my invention is to construct an oiler that will supply a definite amount of oil irrespective of whether the oil is heavy or light.

With these and incidental objects in view, the invention consists in certain novel features of construction and combination of parts, the essential elements of which are set forth in appended claims and a preferred form of embodiment of which is hereinafter described with reference to the drawing which accompanies and forms a part of this specification.

In the drawing, Figure 1, shows a side elevation of the oiler with the essential interior parts dotted in, and Fig. 2 discloses a cross section on the line AA looking in the direction of the arrows. The tank 1, Fig. 1, is adapted to be fastened to the frame of the engine in any suitable manner, so the pinion 2 may be driven by the engine to operate the oiler mechanism. Driven by the pinion 2 the reducing gear 3 is adapted to drive the oiler gear 4 in an anti-clockwise direction, the gear 4 being journaled at 5 in the oiler case 6 so that when the tank and case are bolted together by the bolts 7 and the tank is supplied with oil the gear 4 will carry the droppers 8 swinging loosely on the dropper studs 9 down into the oil in the tank 1, and each dropper will carry upwardly with it a certain amount of oil, which in a continued rotation of the

gear 4 will be wiped off by the wipers 10, the oil from the droppers passing down the wipers into the holes 11, Fig. 2, from where it is lead by pipes to the engine cylinders in any suitable manner.

As shown in Fig. 2 the gear 4 carries a set of droppers on either side and each of the dropper studs 9 carries two droppers, thus providing for the lubrication of the four cylinders.

The adjusters 13, preferably made of wire, and one being provided for each side of the oiler gear 4, serve to determine the amount of oil that will be fed to the engine cylinders. Adjustment holes 14, Fig. 1, are provided, into which the ends 15, Fig. 2, of the adjusters 13 may be sprung and the position of the adjusters in these holes will determine the position of the crank end 12 of the adjuster inside of the oiler case.

The droppers 8 are preferably in sets of three different lengths for each cylinder, and the adjuster crank 12 on the inside of the case is adapted to be so positioned when placed in the lowest adjustment hole that all of the droppers will pass over it during the rotation of the gear 4 without touching it, and thus deposit all of the oil picked up by them on their respective wipers. When the adjuster 13 is placed in the second hole the longest set of droppers will wipe on the crank 12 of the adjuster in passing, and most of the oil will be wiped therefrom, and hence the wipers will receive less oil when the droppers wipe against them. Similarly with the adjuster 13 in the third hole the longest and second longest sets of droppers will wipe on the adjuster crank 12, removing most of the oil, and the remaining short set of droppers will deposit all of its oil on the proper wipers. While if the adjuster is placed in the fourth position, all of the droppers will wipe over the adjuster crank end 12, removing most of the oil from each of the droppers, and only a small quantity will remain to be deposited on the wipers 10.

If the adjuster is placed in the fifth, or last, position all of the droppers will be wiped their entire length and practically all oil removed, so that only a minor quantity will be wiped off by the wipers. It is evident that no matter whether the oil be light or heavy, the droppers will carry with them a drop of oil and lubricant will thus be fed to the engine cylinders under all operating conditions.

While I have thus described my invention with one particular type of oiler and a certain arrangement of parts, I do not wish it understood that I limit myself to this construction, as it is evident that my invention may be embodied in many different ways within the scope of the following claims.

Claims:

1. In an engine cylinder oiler, the combination of an oil reservoir, a rotating member adapted to rotate partly within and partly without said oil reservoir, a stud on said rotating member carrying a dropper, and means adapted to wipe said dropper as it passes by said means.
2. In an engine cylinder oiler, the combination of a reservoir adapted to contain oil, a rotatable member carrying thereon a dropper adapted to be carried into and out of the oil in said tank, means for removing the oil from said dropper after it has been carried from said tank, and adjustable means for wiping oil from said dropper before said dropper reaches said wiping means in its rotation.
3. In an engine cylinder oiler, the combination of a tank adapted to contain oil, rotatable means adapted to carry a series of droppers of different length, a wiper associated with said rotatable means and adapted to wipe all of said droppers as they are carried past during the rotation of said rotatable means, and an adjuster adapted to

be set in different positions, so said adjuster will wipe a greater amount of said droppers in one position than in another position.

4. In an engine cylinder oiler, the combination of a tank adapted to contain oil, rotatable means carrying droppers thereon adapted to always hang vertically therefrom and to have a portion of said droppers carried into and out of the oil contained in said tank by the rotation of said rotatable means, a wiper adapted to wipe all of said droppers, and adjustable means whereby the amount of oil received by said wiper may be varied.

5. In an engine cylinder oiler, the combination of a tank adapted to contain oil, a rotatable member adapted to be driven by the engine to which the oiler is applied, droppers of unequal length suspended vertically on said rotatable member and adapted to be carried into and out of the oil in said tank by the rotation of said rotatable member, a wiper positioned so as to be wiped by said droppers during the rotation of said rotatable members and to receive oil from said droppers during said wiping, means for leading the oil so collected from said wiper, and an adjuster so positioned that it may be set to wipe all of the droppers longer than any predetermined length before said droppers are carried to said wiper.

CHARLES A. STICKNEY.
